(No Model.)

E. NELSON.
SECTIONAL SURFACE CONDENSER.

No. 477,812.

Patented June 28, 1892.

UNITED STATES PATENT OFFICE.

ELIHU NELSON, OF NEW YORK, N. Y., ASSIGNOR OF ONE-HALF TO WILLIAM M. MACBEAN, OF SAME PLACE.

SECTIONAL SURFACE CONDENSER.

SPECIFICATION forming part of Letters Patent No. 477,812, dated June 28, 1892.

Application filed August 1, 1891. Serial No. 401,406. (No model.)

To all whom it may concern:

Be it known that I, ELIHU NELSON, a citizen of the United States, residing at New York, in the county of New York and State of New York, have invented certain new and useful Improvements in Sectional Surface Condensers; and I do hereby declare the following to be a full, clear, and exact description of the invention, such as will enable others skilled

10 in the art to which it appertains to make and use the same.

My invention relates to improvements in sectional surface condensers, and is concerned with various details of such condensers with a view to increasing the efficiency, 15 economizing space, and making apparatus of this class more convenient to handle and easier to repair.

One of the main objects of my improvement is to supply a sectional surface condenser that will occupy a smaller space than the surface condensers now in general use in sea-going and other steamers. At the same time I provide means whereby a large condensing-surface is exposed and whereby a high 20 vacuum may be maintained by returning the water of condensation to my air-pump cool and to the boiler hot. This arrangement economizes fuel and adds to the efficiency of

25 the apparatus. I also provide means whereby one or more sections of my condenser may be cut out either separately or together, as the case may require, while the remaining sections can be used and serve to a great extent the purposes of a condenser, so that the engine may not be wholly deprived of means for condensing the steam, even though some of the sections should be out of use. This

permits a damaged section or sections to be 30 repaired while the engine is in operation. I further provide means whereby one of the sections can be used either as a heating-section or a condensing-section, as may be required.

I further provide a receiver for taking up the 35 water of condensation after it has passed through the heating-section and a safety branch or overflow pipe above the receiver, the said overflow-pipe being connected with the pipe that passes the water of condensation from the heating-section into the re-

ceiver. By these means, as will appear hereinafter, several important improvements are effected, among which is that of relieving the air that the air-pump has drawn from the condensing-sections along with the water of condensation and also that of passing the water of condensation overboard should the boiler-pump fail to work when the engine is in motion.

In carrying out my invention I have devised certain novel details of construction, one of which consists in giving a peculiar shape to the hoods of some of the sections, as will be fully described hereinafter. Another is a by-pass for the steam and the water of condensation. Still another is what I call a "safety-pipe" for relieving the pressure on my first section, when for any reason the boiler-pump fails to act while the engine is at work. Still another consists in making the center tubes larger than the surrounding tubes, the center tubes of the first three sections being somewhat larger than that of the last and somewhat smaller than the steam-exhaust pipe.

My invention also comprises other details of construction, which will be fully set forth in the specification which follows.

My invention is illustrated in the accompanying drawings, in which—

Figure 1 is an elevation, partly sectional, of my sectional surface condenser. Fig. 2 is an end view of sections A, B, and C with the hood removed. Fig. 3 is a similar view of section D, and Fig. 4 shows the cross-sections of the center pipes of sections A, B, C, and D as compared with the cross-sections of the steam-exhaust pipe.

Referring to the drawings by letter, Z is the steam-pipe entering a Y with two outlets, one of which passes through a valve 1 and into the hood a' on the end of section A. The other is a by-pass or branch Z', which passes around the section A and into a two-way cross or coupling T beyond the said section A. The cross or coupling T has two short horizontal pipes connected with it, one of which enters through a valve 3 the hood a'' on the end of section A and the other of which enters through a valve 4 the hood b' on the end

of section B. Another by-pass pipe Z² proceeds from the coupling T through the valve 5, and is joined to a T's, which is set in between the corresponding hoods of sections B 5 and C of my condenser and forms the coupling for the pipes S and S', which join the said sections. In the pipe Z' is a valve 2 and in the pipe S is a valve 6. The connection between the hoods at the other extremity of 10 section C and the corresponding hood on section D is made by means of a short pipe U, as shown in the drawings. From the opposite hood of section D a pipe M proceeds to an air-pump P. Beyond the air-pump is a 15 check-valve C² in a pipe E', which is joined to a vertical pipe E. The latter is connected through a T with the pipe E², in which is a valve 9. The pipe E² is connected through another T with a pipe N, that leads directly 20 into the cylinder of section A, and also with a pipe X', containing a valve 13, the object of which pipe and valve will be explained hereinafter. At the opposite end of the cylinder of section A a pipe F leads out and is branched 25 so as to go through valve 10 into the pipe F', leading to the receiver R, or so as to go through pipe F² and valve 14 to an exit, overboard, or elsewhere. Returning to pipe E, we shall see that it is divided at the T, so as to afford a 30 passage not only in the direction already described, but also through a horizontal pipe V, valves 8 and 17, and pipe H overboard. Moreover, before reaching the valve 17 a T is inserted, which connects the pipe V with a 35 vertical pipe Y, which extends upward and is run into a T in the pipe F². The pipe Y contains a valve 15.

Above the receiver R is led off a pipe F³, which furnishes an exit overboard. At the 40 bottom of the receiver a pipe G, containing a valve 16, is led off and downward to the boiler-pump P'. I place the boiler-pump below the receiver, as the water of condensation which passes into the receiver is hot and the pump 45 would not raise it if it were situated above the receiver.

The sections A, B, C, and D are made up of tubes, which are expanded into or otherwise secured in the tube-sheets. The number of 50 tubes in sections A, B, and C is greater than in section D, for by the time the steam has reached the last-named section it has become greatly condensed. If I were intending to use the different sections in series, I should 55 make them successively smaller for the same reason; but it will be remembered that I may cut out section A or section B, or both, or I may use section A as a heating-section, in which case the steam coming in contact with 60 the surfaces partly heated will not be condensed to so great an extent. In either case it is necessary to make the first three sections of about the same dimension.

The center pipe of sections A, B, and C is 65 somewhat smaller than the steam-exhaust pipe Z and somewhat larger than the center pipe X of section D.

Such being the construction and arrangement of the steam-conducting apparatus, it now remains to describe the water-conducting 70 apparatus, and this will now be done.

The water enters at pipe K, which pipe is branched through suitable T's or couplings into pipes X', K', and K². The pipe X' leads through the valve 13 to the pipe N, which enters the outer chamber of section A. The exit is through valve 11, pipe F, valve 10, pipe F', to the receiver R, or through valve 11, pipe F, valve 10, pipes F' and F³ overboard, or through valve 11, pipes F and F², valve 14, 80 and pipe X² overboard. When the water circulates through pipe X' and passes through valve 13, the valve 9 is closed to prevent the water from passing down in the pipes E² and E into the air-pump. The pipe K' extends 85 down to the chamber of section C and enters it, the exit from said chamber being accomplished through a pipe I, which connects that chamber with the chamber of section D. From the chamber of section D leads a pipe 90 O, in which is a check-valve C'. Beyond the check-valve a pipe L is joined on, which extends upward, and is connected by a T with the pipe J', leading overboard, and the pipe J, which forms the exit-pipe of the other 95 chamber of section B. In the pipe J is a valve 12. The branch pipe K², already mentioned, has in it a valve 7, beyond which it enters the outer chamber of section B.

By observing the arrows which indicate the 100 course of the steam, beginning at the entrance of pipe Z it will be seen that the steam passes through sections A and B (when they are in use) in a direction from right to left and that it passes through section C in a direction from 105 left to right and through section D in a direction from right to left again. It is also evident that the direction of flow in sections C and D is not altered by the cutting out of either or both of the sections A and B, nor is 110 the direction of flow in either A or B affected by the circumstance that one or the other is cut out. If now the direction of flow of the induction-water is studied, beginning at K and referring to the arrows it will be seen that the 115 water flows through the outer chambers and circulates around the pipes in a direction opposite to that taken by the steam. This is true of the water which passes through pipe X', valve 13, and pipe N into and through the 120 chamber of section A. It is also true of the water which passes through pipe K' and the chamber of section C and pipe I' and the chamber of section D. It is also true of the water 125 which circulates through pipe K², valve 7, and the chamber of section B. I construct the apparatus in this way with the object of attaining greater efficiency in its use as a condenser, as I find that by this arrangement I am able to use fewer sections than would be 130 the case if the water and the steam flowed in the same direction.

Another special feature of the construction and arrangement described is that the induc-

tion-water is passed cold into three of the sections, thereby producing a greater condensing effect than if the water passed successively from one section to the next. In that case the 5 water would become heated as it passed along and exert less effect in condensing the steam.

Coming now to the special construction of the parts, the receiver R is made of a piece of pipe standing in a vertical position with a 10 reducing-coupling screwed upon the upper end where the pipe F' enters. At the bottom of the receiver a cap is screwed on with a side opening to connect with the pipe G, running to the boiler-pump, as already described.

15 I have adopted a special construction for the hoods, which are secured to the ends of the sections by flanged joints. The hoods a' and b', through which, respectively, the steam enters sections A and B, are constructed of 20 the usual shape—that is, they are semicircular—and the connecting-pipes enter them at the middle. With the other hoods, however, one side is made straight instead of curved, and the connecting-pipes enter either directly 25 from the straight side or, as in the hood a', through the curved portion just alongside the straight side. I find that with the semicircular hoods the water of condensation is sure to collect in such quantity as to form a back- 30 pressure upon the steam, to say nothing of the loss which takes place by reason of the water not flowing through either by gravity or under the action of the air-pump. By examining the drawing of the hood a' it will be 35 seen that the connecting-pipe enters its lowest portion, so that all the water which collects in the hood can easily be drawn off by the air-pump. Furthermore, in the case of the hood b' all the water which collects will pass 40 out by gravity, as the pipe S is joined to the hood through the lower flat portion thereof. Obviously the same action will take place in the other hoods which form the outlet of sections C and D. It will be seen that I make 45 the upper portions of the inlet-hoods of the said sections flat and horizontal, so that the said hoods may be connected with the outlet-hoods out of the sections just preceding by straight vertical pipes, which allow the water 50 of condensation to fall through them without obstruction. The hoods and the outer chambers of the different sections are provided with hand-plates *i i i*, which can be removed for the purpose of inspecting or cleaning the 55 respective parts. Drip-cocks *a a a a* are placed at the lowest points in the various pipes for emptying the condenser of its contents when necessary. The hoods, being connected to the condenser-sections by flanged 60 joints, can be easily removed when it is necessary to make repairs.

In Fig. 2, W is the center tube of sections A, B, and C, and in Fig. 3 X is the center tube of section D. Fig. 4 shows these same tubes 65 in cross-section alongside the steam-exhaust tube Z. The relative sizes are clear from these figures.

The operation of the apparatus under varying conditions will now be described. Suppose, for example, that it is desired to use section A as a heating-section. In that case valves 1, 3, 4, 6, 9, 11, 10, 16, 7, and 12 are open and valves 8, 17, 15, 2, 14, 13, and 5 are closed. The steam enters at Z, passes through valve 1 into the hood a', then through the tubes into the hood a², thence through valve 3, coupling T, valve 4, the hoods and tubes and section B, pipe S, valve 6, T^s, pipe S', and the hoods and tubes of sections C and D, as indicated by the arrows. As the steam has become condensed 70 the air-pump P draws the water of condensation from the section D through pipe M and passes it through the check-valve C^s, pipe E, and valve 9 into the chamber of section A to be heated before passing into the receiver. 75 In the chamber of section A the water of condensation circulates around the tubes and passes out through valve 11, pipe F, valve 10, and pipe F' into the receiver. Whatever air the air-pump has drawn from the condenser-sections along with the water of condensation 80 will pass over the same course and out through the branch pipe F^s. The said pipe F^s acts also as an outlet for the water of condensation in case the boiler-pump should from any cause 85 fail to act while the engine is in motion. The boiler-pump takes the water from the receiver through the valve 16 and pipe G. Supposing section A is to be used for a condensing-section. In that case valves 1, 3, 4, 6, 8, 17, 12, 100 13, 7, 11, and 14 are open and valves 2, 5, 9, 15, 16, and 10 are closed. The steam enters at Z and traverses the course already described as being taken by the steam when the section A is used as a heating-section as far 105 as the pipe E. From that pipe it passes through pipe V, valves 8 and 17, and pipe H overboard. The cooling-water for the condensing-section A is taken from the branch pipe X^s after it has passed through valve 13 110 and pipe N into the chamber of section A. Beyond the said section, after circulating around the tubes, the water passes through valve 11, pipes F and F^s, valve 14, and pipe X^s overboard. 115

Suppose it is desired to cut out section A and use the remaining sections, returning the water of condensation through a by-pass to the receiver. Valves 2, 4, 6, 8, 15, 16, 10, 7, and 12 are open and valves 17, 9, 13, 5, 3, 11, 1, and 14 are closed. The steam entering at Z passes through valve 2 and by-pass pipe Z', and after reaching the cross or coupling T will pass through the open valve 4 and over the course already described to the pipe E, thence by the pipe V, valves 8 and 15, and by-pass pipe Y to the pipe F^s, valve 10, pipe F', and receiver R. From the receiver the boiler-pump carries the water through valve 16 and pipe G. 120

Suppose it is desired to cut out section B 130 for repairs or any other reason. Valves 1, 3, 5, 9, 11, 10, and 16 are open and valves 2, 4, 6, 7, 12, 13, 14, 8, 15, and 17 are closed. Valve 12 is placed in the eduction-water pipe of sec-

tion B to keep the cooling-water from backing up into the said section from sections C and D when section B is cut out, and valve 6 similarly prevents the steam from backing up into section B when the said section is cut out. The arrangement of valves described is made when section B is cut out and section A is to be used as a heating-section. In that case the steam enters at Z, passes through valve 1 and the hoods and tubes of section A, valve 3, and cross or coupling T, through valve 5 and by-pass pipe Z², through the hoods and tubes of sections C and D, pipe M, air-pump P, check-valve C', pipe E, pipe E², valve 9, chamber of section A, valve 11, pipe F, valve 10, pipe F', receiver R, valve 16, pipe G, and boiler-pump; but if section A is to be used as a condensing-section while the section B is cut out valves 1, 3, 5, 13, 11, 14, 8, and 17 will be open and valves 2, 10, 4, 6, 7, 12, 9, 15, and 16 will be closed. In that case the cooling-water will pass from pipe X' through valve 13 and pipe N into the chamber of section A, and will pass out overboard by way of valve 11, pipes F and F², valve 14, and pipe X². At the same time the water of condensation will pass from pipe E through V, valve 8, valve 17, and pipe H overboard.

Suppose sections A and B are both cut out and that it is desired to pass the water of condensation into the receiver. In that case valves 1, 3, 4, 6, 9, 11, 14, 7, 12, 13, and 17 are closed and valves 2, 5, 8, 15, 10, and 16 are open. The steam enters at Z and being shut off by the closed valve 1 passes through the open valve 2 and the pipe Z², constituting a by-pass to the cross or coupling T. Thence it goes by the only course open through the valve 5 and the by-pass pipe Z², whence it enters the hood of section C and travels over the usual course to the pipe E, valve 8, pipes V and Y, valve 15, to the pipe F², valve 10, pipe F', and receiver R. Thence it goes to the boiler-pump, as already described; or, if it is not desired to have the boiler-pump draw it from the receiver the valve 16 can be closed and the water of condensation can be passed overboard after it has filled the receiver through branch or safety pipe F³. I call the open pipe F³ a "safety-pipe," because if the boiler-pump should fail to act while the engine continued in motion section A would burst, unless there were an outlet provided such as I have made by means of the pipe F³. The only valve needing to be changed is the valve 16, which shuts off the water from the boiler-pump and allows the receiver to get filled and the water to be forced overboard through the pipe F³. If it is desired to pass the water of condensation overboard without going into the receiver, valve 15 will be closed and valve 17 open. The water will pass through valve 17 and pipe H overboard. Besides closing valve 15 valves 10 and 16 may also be closed, the other valves being unchanged. The cooling-water will enter the chamber of section C through the branch pipe

K', connected to the main induction-water pipe K, and it will pass through the chambers of sections C and D and out through the pipe O, check-valve C', and pipes L and J overboard.

Suppose all the sections A, B, C, and D are to be used as condenser-sections, the steam passes successively through the hoods and tubes of the different sections and to the pipe E by the course already described, and thence through pipe V, valves 8 and 17, and pipe H overboard. The induction-water is conveyed into the condenser-sections from the main induction water-pipe K through the branches X, K', and K² in such a manner that each of the first three sections of my condenser gets a separate supply of cooling-water. For example, A gets its supply through the pipe X' and N, the exit being through valve 11, pipes F and F², and valve 14 overboard. Section B gets its supply through the pipe K² and valve 7, the exit being by way of pipe J, valve 12, and pipe J' overboard. Section C (and with it section D) gets its supply through the branch pipe K', the exit from section D being by pipes O and L and J' overboard, passing on the way check-valve C'. It will be seen that while there is a common ejection-pipe J' for the sections B, C, and D, yet the first-named section discharges its cooling-water separately through the said pipe and section C discharges its cooling-water through pipe I and the chamber of section D, and thence through pipe O, check-valve C', and pipe K to the same exit. Instead of passing the cooling-water after it has traversed the section A through the valve 14 and overboard, this valve can be closed and valve 10 opened, whereupon the water will pass into the receiver R through the pipe F'. It can then be used in the boiler, passing through for the purpose valve 16, pipe G, and the boiler pump; or if this water is not wanted for the boiler, valve 16 can be closed and the water passed overboard through the safety overflow-pipe F³.

When all the sections A B C D are used as condenser-sections and the cooling-water which traverses section A is passed overboard through valve 14 and pipe X², the arrangement of opened and closed valves will be as follows: open, 1, 3, 4, 6, 8, 17, 7, 12, 13, 11, and 14; closed, 2, 5, 9, 15, 10, and 16. To pass the cooling-water from section A into the receiver, the arrangement will be the same, except that valve 14 will be closed and valve 10 open. To pass the water through the receiver to the boiler-pump, valve 16 will also be open. In other words, the final arrangement of the valves will be: open, 1, 3, 4, 6, 8, 17, 7, 12, 13, 11, 10, and 16; closed, 2, 5, 9, 15, and 14. Closing valve 16 will have the effect of forcing all the water to pass off through the safety branch pipe F³ above the receiver.

It may happen that the water passing through section A when it is used as a heating-section will get too hot for the boiler-pump to work well, in which case the valve 2

may be partially opened to allow a part of the steam to go through the by-pass and enter section B. In this way the temperature of the water passing to the boiler-pump can be regulated, and if all of the sections of the condenser are used as condensing-sections valve 2 of the by-pass may be fully opened, if so desired, to divide the steam by letting part of the steam pass through the by-pass and part 10 through the first section. The condenser, as constructed for actual use, will have ample cooling-surface to condense the steam without the first section, and for this reason when all of the sections are used as condensing-sections the steam may be divided, as before stated, so that the steam will have a chance to expand suddenly after leaving the main steam-exhaust pipe, making it easier on the condenser and engine.

20 It will be observed that the heating-section A has a hand-hole and a hand-plate both at the top and bottom, the latter hand-hole being there to permit the water used in cleansing the chamber to pass out.

25 When section B is cut out for repairs, the condenser is deprived of one of its condensing-stations, but in that case section A may be used as a condensing-section, and the heating-section dispensed with.

30 I claim as my invention—

1. In a sectional surface condenser wherein a series of condensing-sections are arranged consecutively, the combination, with a large center tube, of smaller tubes surrounding the 35 same in every section, the center tube in the last section of the series being diminished in size and having a smaller number of tubes surrounding it as compared with the other sections, substantially as shown and described.

40 2. In a sectional surface condenser, a series of tubular steam-condensing sections, each section having a center tube larger than the surrounding tubes and the last section having a center tube reduced in size as compared 45 with the preceding sections, substantially as shown and described.

3. In a sectional surface condenser, a series of sections, the first two or more of which are of the same dimensions, while the last section 50 or sections are diminished in size, in combination with suitable by-passes whereby either of the first group of sections can be cut out at will, substantially as shown and described.

55 4. In a sectional surface condenser, a series of sections connected by suitable pipes containing valves, one of the said sections being provided with an exit both to the boiler and to the open air, whereby the said section can 60 be used either as a heating or a condensing section, substantially as shown and described.

5. In a sectional surface condenser, a series 65 of sections connected by suitable pipes containing valves, one of the said sections being provided with exits both to the boiler and to the open air, and the same section being also provided with inlets connecting both with

the induction water-pipe and with the pipe conveying the water of condensation, substantially as and for the purpose set forth. 70

6. In a sectional surface condenser, a receiver located between the exit-valve for the water of condensation and the boiler-pump, the receiver having a vent to the open air and being adapted to receive the water of condensation after it has passed through the heating-section and before it goes to the boiler-pump, substantially as shown and described. 75

7. In a sectional surface condenser, a receiver located in the exit-pipe before it reaches the boiler-pump, in combination with a safety branch pipe F open to the air and situated above the receiver, as and for the purpose set forth. 80

8. In a sectional surface condenser, a receiver located between the heating-section and the boiler-pump, in combination with a by-pass around the said heating-section, substantially as shown and described, whereby 90 the water of condensation can be passed into the receiver without traversing the heating-section.

9. In a sectional surface condenser, a series of sections connected by suitable pipes containing valves, one of the said sections being provided with exits both to the open air and to the pipe which leads toward the boiler-pump, the said last-named pipe containing a receiver and a valve for closing or opening 100 the passage through the same and also being joined to a pipe which I call a "safety branch" pipe opening to the air and situated above the receiver, substantially as shown and described. 105

10. In a sectional surface condenser, a series of sections connected by suitable pipes containing valves, one of the said sections being joined to the inlet-pipe for the water of condensation and also to a branch from the 110 main induction water-pipe.

11. In a sectional surface condenser, a heating-section which is connected by a branch pipe with the main induction water-pipe, and an exit for the said heating-section leading 115 toward the boiler-pump, whereby, if desired, the water of induction can be heated for passing to the boiler, substantially as described.

12. In a sectional surface condenser, a series of sections connected by suitable pipes, 120 an outlet for the water of condensation, the said outlet-pipe being led directly to the heating-section, and a branch of the said outlet-pipe, forming a by-pass which connects with the exit-pipe from the heating-section beyond 125 the said section and another branch of the said outlet-pipe leading to the open air, all in combination with suitable valves for shutting off the water of condensation from any one or more of the said pipes or branches and 130 allowing it to pass through any other of the said pipes or branches, substantially as shown and described.

13. In a sectional surface condenser, a se-

ries of sections connected by suitable pipes, in combination with by-pass pipes which cut out one or more of the said sections, while leaving the others operating, substantially as shown and described.

14. In a sectional surface condenser, a series of condensing-sections connected by suitable pipes, in combination with a main induction water-pipe having branches which run directly to two or more of the said sections, whereby the full effect of the cold water of induction may be brought to bear upon the steam at several different points and at several degrees of condensation, substantially as shown and described.

15. In a sectional surface condenser, a series of condensing-sections, in combination with the main induction water-pipe having three branches, one of which is connected to the first section, another to the second section, and the third to the remaining sections, substantially as shown and described.

16. In a sectional surface condenser, the hoods having one side flat and located horizontally and opposite each other, the corresponding flat sides facing each other, as shown, so that they can be connected by a straight vertical pipe, whereby the water of condensa-

tion will flow of its own gravity from one hood to the next, as set forth.

17. In a sectional surface condenser, a receiver constructed of a section of pipe placed in a vertical position and having a reducing-coupling screwed upon its upper end and on its lower end a cap with a side opening, as and for the purpose set forth.

18. In a sectional surface condenser, a receiver having a vent to the open air and being located in the exit-pipe for the water of condensation, and a boiler-pump located in a position below the said receiver, as and for the purpose set forth.

19. In a sectional surface condenser, a heating-section, and a steam-exhaust pipe leading thereto and containing a valve, in combination with a by-pass, also containing a valve, whereby the amount of steam passing into the heating-section may be regulated, as and for the purpose set forth.

In testimony whereof I have signed my name, in the presence of two witnesses, this 29th day of July, A. D. 1891.

ELIHU NELSON.
